UNITED STATES PATENT OFFICE.

ALEXANDER F. JENKINS, OF BALTIMORE, MARYLAND.

CARBID-HOLDER.

1,304,685.

Specification of Letters Patent. Patented May 27, 1919.

Application filed April 17, 1918. Serial No. 229,106.

To all whom it may concern:

Be it known that I, ALEXANDER F. JENKINS, a citizen of the United States of America, residing in the city of Baltimore, 5 State of Maryland, have invented certain new and useful Improvements in Carbide-Holders, of which the following is a specification.

In my co-pending application, Serial No. 10 184,195, I have described a generator having as a carbide receptacle a series of tapering overlapping pockets, the arrangement of which is preferably in the form of a spiral or helix. The pockets as shown are supported on radially placed plates having apertures for the flow or feed of the water, shown as overlapping in the intersecting horizontal planes and spirally or helically arranged to correspond to the pockets so 15 that the feed may be described as spiral or helical. The carbide is wetted gradually according to the demand for or consumption of gas without any sudden increases or cessations of generation except in correspondence 20 with the demand. The spiral arrangement of the tapering, preferably conical, pockets also has the advantages that it supports the increasing bulk of the carbide as it is acted upon by the water and the tapering pockets 25 are easily emptied and refilled on recharging the generator.

With pockets of the old types having a flat bottom surface so that when the water reaches the pocket, the entire cross-section 30 of carbide in the container is immediately submerged, a sudden increase in rate of generation results, or generation may drop off entirely or become much less than the demand when the water level reaches a space 35 between the containers so that it engages no new carbide.

The object of the present invention is to produce a carbide supporter having a single container presenting a constant horizontal 40 cross-section of the carbide at each water level, or, if desired, the cross-section of material wetted may be slightly increased as the water level approaches the top. This holder also has the advantages of accessibility 45 for filling and emptying with room and support for the consumed material.

In the present instance, in order to produce a carbide support presenting equal or substantially equal cross-section to the water 50 at each level, I have made the carbide holder in the form of a helix, or in a form ap-

proaching a helix, the vertical transverse section of the elongated container, which may be referred to as wound about the central core or support, being preferably V-shaped 60 or tapered. This holder is shown as perforated and provided with transverse partitions to prevent the flowing or slipping of the carbide down the incline of the helix. These partitions or radiating plates may to 65 advantage be perforated to provide for the spiral or helical feed or flow of the water to the carbide.

In the accompanying drawing, I have illustrated a generator equipped with a 70 carbide holder in accordance with my invention in the preferred form.

Figure 1 is a vertical central section through the generator, showing the carbide holder in elevation; and

Fig. 2 is a section on the line 2, 2 of Fig. 1.

Referring to the drawings by numerals, I have shown an outer casing 1, an inner inverted drum or cylinder 2, a cylindrical 80 casing 3 inside the drum, a gas pipe 4 leading upward from the top of the drum and downward through the liquid in the tank toward the washer 5. From a point near the washer 5 at the bottom, a delivery pipe 6 85 leads upward to the top of the tank. The entire apparatus is water-sealed, the water normally having its top level near the top of the tank. To accomplish the water-sealing, the pipes 4 and 6, that is the pipe 4 leading 90 from the top of the drum 2 downward to the bottom of the tank, and the pipe 6 leading from the bottom of the tank outward to the delivery valve 7, are of comparatively large cross-section, the washer having small 95 pipes 8, 9 leading therefrom to points above the water level and telescoped within the corresponding pipes 4, 6. The drum 2 is inverted in the water, being at the beginning of generation filled with air which keeps the 100 water from entering the drum, the pressure in the drum being supplied by the depth of water in the tank. These features are described and shown in my co-pending application.

The important feature of the present invention is found in the contour and arrangement of the carbide holder or support. This may be properly described as an elongated container of downwardly tapering transverse cross-section, *i. e.*, of decreasing width from the top toward the bottom of the ver-

tical transverse cross-section, the elongated container being wound about a central upright or axis in the form of a helix or spiral. This elongated container, which is 5 preferably of tapering cross-section, is indicated by reference character 10, the same having a central upright support or axis 11 about which it is wound, in the form of the invention illustrated, substantially in a helix. 10 It is also provided with transverse partitions 12 arranged at intervals to prevent undue settling of the material down the incline of the helix. These partitions may to advantage be perforated as indicated by the aper- 15 tures 14 on the drawing, the perforations tending to give the water a helical feed along the container. At the bottom, the support has a foot or rest which may be in the form of a cross to engage the shelf 15 20 on the inside cylinder 3, the latter resting on the radiating portions of the pipes 8 and 9, or any other suitable support.

When the apparatus is operatively assembled, the carbid support or container is 25 closed within the inverted drum 2, submerged in the water in the external tank, the water being excluded from the drum by the air impounded therein. When the delivery valve is opened, a portion of the air escapes, the water rises and wets the carbid and generation begins. Thereafter, the level 30 of the water advances as the carbid is consumed, the level of the water which regulates generation being controlled by the gas 35 pressure which is in turn controlled by the relation of the rate of consumption to the rate of generation, so that with a uniform or substantially uniform cross-section of carbid exposed to the action of the water at all 40 levels, the rate of generation after the apparatus is once started becomes and remains equal to or very nearly equal to the rate of consumption.

With the apparatus described which 45 consists of an elongated receptacle for the carbid, preferably tapered in transverse cross-section, wound spirally or helically about a central axis or support, there is a constant 50 or nearly constant cross-section of carbid at each level exposed to the action of the advancing water. While this has been referred to as substantially constant or substantially equal at all points, it is evident 55 that owing to the variation in pressure be-

tween the bottom and the top of the drum, it may be found desirable to vary to some degree the cross-section exposed. This variation is slight and is determined by experiment, the adjustment being accomplished 60 either by changing the pitch or cross-section of the elongated, spirally arranged container. In the present instance the pitch is decreased toward the top, giving a corresponding increase of horizontal cross-section 65 from the bottom to the top of the container. This container may be made of perforated sheet metal, as shown, or of wire mesh. The container which is, broadly speaking, of perforated material, is preferably provided with 70 transverse partitions as shown to keep the material from settling down the incline of the spiral. The partitions as shown, are apertured so that the water passes freely through them giving a spiral feed in the 75 direction of the length of the container.

This device also has the advantage that the container is tapered from the bottom toward the top at each and every point of its length, providing a large top area to 80 support the increased bulk of the carbid due to expansion which takes place as it is consumed. Also, the opening at the top spiral surface 16 of the container is exposed at all points providing convenient access for 85 filling and easy loosening and removal of the ashes or consumed carbid.

I have thus described my invention specifically and in detail in order that its nature and operation may be fully understood; 90 however, the specific terms herein are used descriptively rather than in their limiting sense and the scope of the invention is defined in the claim.

I claim—

In an acetylene generator, a support for 95 the carbid, the same consisting of an elongated, perforated container of tapered cross-section arranged substantially in an upright spiral of a plurality of turns, the container 100 having transverse partitions, the partitions being apertured for the passage of the water.

Signed by me at Baltimore, Maryland, this 5th day of April, 1918.

ALEXANDER F. JENKINS.
